Fig. 9.

26

A technical drawing of a mechanical assembly. It features a U-shaped frame with a vertical leg on the left. A horizontal bar extends from the right side of the frame. Several components are labeled: '87' is written above the left vertical leg; '30' is written above the top horizontal bar; '110' is written above the middle of the horizontal bar; '111' is written above a circular hole on the right side; '112' is written below the vertical leg; and '21' is written below the right side of the horizontal bar. The drawing is done in black ink on a white background.

UNITED STATES PATENT OFFICE.

ALVA W. TYLER, OF CHICAGO, ILLINOIS, ASSIGNOR TO THE AMERICAN CEMENT
PLASTER COMPANY, OF CHICAGO, ILLINOIS, A CORPORATION OF KANSAS.

CUTTING MACHINE.

1,417,117.

Specification of Letters Patent. Patented May 23, 1922.

Application filed November 15, 1919. Serial No. 338,190.

To all whom it may concern:

Be it known that I, ALVA W. TYLER, a citizen of the United States, and a resident of Chicago, in the county of Cook and State 5 of Illinois, have invented certain new and useful Improvements in Cutting Machines; and I do hereby declare that the following is a full, clear, and exact description thereof, reference being had to the accompanying 10 drawings, and to the letters of reference thereon, which form a part of this specification.

This invention relates to improvements in cutting machines, and consists of the matters hereinafter described and more particularly pointed out in the appended claims.

The object of the invention is to provide an efficient, automatic machine, which will cut or sever a continuous, moving strip or 20 web, into predetermined lengths. The several advantages of the invention will more fully appear as I proceed with my specification.

The invention is herein illustrated and described as embodied in a machine more particularly adapted for use in operating upon a continuous strip or web of plaster board, comprising top and bottom coverings or fibrous material and an intermediate plaster 30 body adhered thereto.

In the drawings:

Fig. 1 illustrates a view in side elevation, of a cutting machine embodying my invention.

Fig. 2 illustrates a top plan view thereof.

Fig. 3 illustrates a transverse vertical sectional view through the cutting machine, the plane of the section being indicated by the line 3-3 of Fig. 1.

Fig. 4 illustrates on an enlarged scale, the valve actuating mechanism shown in Fig. 3.

Fig. 5 illustrates a detail, transverse vertical sectional view through the valve mechanism and piston, the plane of the section being indicated by the line 5-5 of Fig. 2.

Fig. 6 illustrates a longitudinal vertical detail sectional view through the inlet valve mechanism, the plane of the section being indicated by the line 6-6 of Fig. 5.

Fig. 7 illustrates a longitudinal vertical detail sectional view through the power cylinder, the plane of the section being indicated by the line 7-7 of Fig. 5.

Fig. 8 illustrates a perspective view of

one of the valve actuating stems and will be 55 more specifically referred to later.

Fig. 9 illustrates a transverse, vertical sectional view through a part of the cutting machine, the plane of the section being indicated by the line 9-9 of Fig. 1.

Fig. 10 illustrates, on an enlarged scale, a longitudinal vertical detail sectional view through a part of the cutting machine, the plane of the section being indicated by the line 10-10 of Fig. 2.

Fig. 11 illustrates a vertical detail sectional view through a part of the machine, the plane of the section being indicated by line 11-11 of Fig. 4.

Fig. 12 illustrates another vertical detail sectional view through a part of the machine, the plane of the section being indicated by the line 12-12 of Fig. 2.

Fig. 13 illustrates a longitudinal, vertical sectional view, the plane of the section being 75 indicated by the line 13-13 of Fig. 3.

Figs. 14-15 and 16 illustrate horizontal detail sectional views, the planes of the various sections being indicated respectively by the lines 14-14, 15-15, and 16-16 of 80 Fig. 3.

Fig. 17 illustrates a longitudinal vertical detail sectional view through parts of the machine, the plane of the section being indicated by the line 17-17 of Fig. 4.

Figs. 18 and 19 illustrate, on an enlarged scale, sectional view through fragments of plaster board and the knives of the machine, showing the relative position of the knives before and after cutting the plaster board.

Referring now in detail to that embodiment of the invention illustrated in the accompanying drawings, 20-20 indicate upright transversely spaced columns, which are rigidly connected at their ends by top and bottom bridge heads 21 and 22 respectively. Mounted at their ends in said columns are top and bottom cutter bars 23 and 24, which move vertically, towards and away from each other. At the middle of said columns, 100 are outwardly extending, vertically spaced lugs or ears 25, arranged in pairs, each pair receiving between them, longitudinally extending channel beams 26, said ears and the top and bottom flanges of said beams being 105 bolted together. Said beams which are of a suitable length, have affixed to their ends, extensions 27 in the form of edgewise ar-

ranged flat bars, which are movably supported between flanged rollers 28, carried by upright bracket standards 29, fixed to longitudinal stringers 30. 31 and 32 respectively indicate cylinders fixed on associated shafts 31^a and 32^a, which are journalled in bearing blocks 31^b and 32^b, on the stringers 30. Trained about each cylinder is an associated conveyor belt 33 and 34 respectively, the top laps of which are arranged in a plane between the cutter bars and movably support the plaster board 35 to be operated upon.

Each cutter bar has vertical end ribs 23^a and 24^a respectively, which have sliding guided bearing in vertical grooves 20^a—20^a, formed in the inner surfaces of the columns 20 (see Figs. 3, 14 and 16) and near said ends are provided sockets 36, 37, in which are arranged heavy expansion coiled springs 38, that engage on opposite faces of abutments or rests 39, attached to the columns 20, between the lugs or ears, 25 thereon.

In the top and bottom opposed edges of the cutter bars are longitudinal grooves 40—40, in which knives 41—41 are held by bolts 42 (see Fig. 13) said knives having V-shaped cutting edges.

The bottom cutter bar 24, is provided near its end with short, horizontal stub shafts 43, on which are pivotally mounted ears or lugs 44, in which are secured the bottom ends of upright connecting rods 45. The top ends of said rods are also fixed in cross lugs or ears 46, arranged between the top cutter bar 23 and bridge-head 21, which cross lugs are pivoted on studs 47, on the outer ends of rocking levers 48. Said levers 48, which are arranged in the vertical plane of the cutter bars, are pivoted near their outer ends, to rock in a vertical plane, between ears 49, depending from the bottom surface of the top bridge-head 21. The inner ends of said rocking levers are pivotally connected to each other and to the bottom end of a connecting rod 50, by a pin 51. The top end of said connecting rod is connected by a wrist pin 52 (see Fig. 5) to a single acting piston 53, operating in a vertically disposed cylinder 54, which opens downward through the bottom of the bridge-head 21 at its middle. Interposed between the rocking levers 48 and the top cutter bar 23, are anti-friction devices 55 which are seated in recesses provided therefor in the top surface of the cutter bar and on the bottom surface of the bridge-head 21 on each side of the cylinder 54 are provided yielding bumpers 56, against which said levers engage in the 60 return to their normal position.

It is apparent that when the piston 53 moves downwardly on its power stroke, it will depress the inner ends of the levers 48 to move the top cutter bar 23 downwardly 65 and the bottom cutter bar 24 upwardly by

reason of the mechanism just described, both against the action of the springs 38, which returns all parts to their normal positions after the power stroke of the piston has been completed.

In the bridge-head 21 are provided two longitudinal extending, horizontal valve chests 60 and 61, arranged on opposite sides of the cylinder 54. The valve chest 60, contains the inlet valve for the pneumatic operating fluid, preferably steam, to the cylinder 54, while the valve chest 61 contains the exhaust valve for said cylinder. An inlet port 62, which opens through the top of the bridge head 21, 70 connects the valve chest 60 with a pipe 62^a, for the operating fluid, said pipe being connected in a suitable manner with a source of supply. A cross port 63, which connects both valve chests together, opens into the top end of the cylinder 54, and connected with the valve chest 61 is an exhaust chamber 64, to which connects an exhaust pipe 65, which leads to a suitable place of disposal for the exhaust operating fluid. 90

In each valve chest is a tubular valve bushing 66—67 having a driving fit therein, the ends of said bushing being closed by front and rear cover plates, 68 and 69 respectively, which are bolted on opposite sides 95 of the bridge head 21. Each valve bushing has a plurality of longitudinally arranged annularly spaced ports 66^a and 67^a respectively, which open into the cross port 63 and each valve bushing also has an enlarged, 100 longitudinally arranged port 66^b and 67^b, which open into the inlet port 62 and exhaust port 64 respectively. In each valve bushing is rotatively mounted an oscillatable tubular valve plug 73 and 74, having front 105 and rear end walls 75 and an intermediate wall 75^a, said end walls engaging the plates 68, 69 before referred to. In the peripheral part of said valve plugs are provided a plurality of longitudinally arranged, spaced vanes or ribs 76, which normally close off the ports 66^a—67^a in the valve bushings 66 and 67. Diametrically opposite the vanes 76, is a web 77, which connects the end and intermediate walls of the valve plug to strengthen 110 the same as a whole, the space between said web and ribs on the one hand also providing an opening which register with the inlet and exhaust openings 66^a and 67^b respectively, of the valve bushings. In the rear end wall 115 75 of each valve plug, is a transverse groove 80, in which is arranged the cross bar 81 of a cylindrical valve stem 82 (see Figs. 6 and 7).

Said stems project through openings in 125 the plate 69 and their outer ends are journalled in bearings carried at the ends of bracket extensions 83 on said plate 69. A stuffing box 84 is provided about that part of each valve stem where it extends through the 130

said plate 69. A plate 85 connects the bearing sleeves at the outer ends of the brackets 83 together, said plate having annular end flanges which are bolted to said bearings.

5 Keyed to the outer end of each valve stem are lever arms 86 and 87 respectively, which extend towards the adjacent outer ends of the bridge head 21. (See Figs. 3 and 7). A contractile coiled spring 88, which is connected at its ends to the arm 86 and to a bracket 89 extending rearwardly from the bridge head, normally holds the arm 86 against a stop 90 carried by the outer end of that bracket 83 of the plate 69, in which the 10 outer end of the associated valve stem has bearing. The other arm 87, which is likewise connected by a spring 88^a to a similar bracket 89^a, has an extension 87^a, which engages beneath a shoulder 91, on the upright 15 arm of a bell crank trip lever 92, which is pivoted on a rearwardly extending lug carried by plate 85. A spring 93, interposed between a fixed part of said plate and said upright arm of the bell crank lever 92, normally holds the said arm in locking position 20 with respect to the extension 87^a.

Fixed at its ends to the bridge head 21, and bracket 89, respectively, is a strap 94, and pivoted at their middles, on said strap, 25 in the plane of the arm 86, are fingers 95 and 96 respectively. The outer end of the finger 95 is connected by a universal joint to an upright, reciprocable, actuating rod 97, while the inner end of said finger rests in 30 engagement upon the outer end of the finger 96. The inner end of said finger 96 engages beneath the outer end of the arm 86. It is apparent that when an upward movement is imparted to the rod 97, an upward 35 movement will be imparted to the end of the arm 86 against the action of the spring 88, by means of the fingers 95 and 96.

To actuate the bell crank tripping lever 92, to release the extension 87^a of arm 87, I 40 provide the following:—

The end of the horizontal arm of the bell crank tripping lever 92, is bifurcated and through it extends a rod 100, on the top end of which are threaded nuts 101, providing 45 an adjustable shoulder thereon (see Fig. 17). The bottom end of the rod is suitably connected with the rear end of a lever 102, which is pivoted between its ends to a strap 103, depending from the plate 85 before 50 mentioned. The other, or front end, of this lever, has a pin and slot connection with the rear end of a second lever 104, which is pivoted on a strap 105, carried by that bracket 83 associated with the arm 86. The 55 inner end of the lever 104, is connected by a suitable bent link 106, to the pin 51, which connects the levers 48 to the connecting rod 50 of the piston 53. The connection is such that when the piston has moved downwardly, the link 106 will through the levers 60 65 104 and 102, produce a similar movement of the rod 100, when the nuts 101 will engage the bifurcated end of the horizontal arm of the bell crank tripping lever 92, and cause it to withdraw its shoulder 91 from engagement with the extension 87^a of the arm 87. The spring 88^a will then swing the arm 87 downwardly until it engages a stop arm 90^a carried by that bracket 83 associated with the arm 87. To return the arm 87 to its 70 normal position wherein its extension 87^a is engaged beneath the shoulder 91 of the tripping lever 92, I provide the following mechanism: 110 indicates an L shaped lever which is pivoted at 111 on the rear face of 75 a web of the bridge head 21, to swing in a vertical plane, parallel to the longitudinal median line of the machine as a whole (see Fig. 11). The free upright end of said lever extends into the path of the lever 87^a and to said lever 110 is pivoted, the top end of a link 112, the bottom end of which is connected to the lever 48, associated with the exhaust valve mechanism. As the long arm 80 of said lever 48, swings upwardly in its return movement the link 112 will impart a 85 like movement to the member 110, which in turn will swing the outer end of the lever 87 upwardly. This will cause the short arm 87^a thereof to move downwardly, its inclined 90 end surface engaging the top end of the arm 95 91 of the trip lever and moving the same so as to engage beneath the shoulder of said arm.

As before mentioned, the supporting channel bars are movably mounted with respect to the standards 29 and movement is imparted first in the direction of the travel of the material being operated upon, so that said material is cut by the knives as it moves 100 with the supporting belts 23—24 and then in a reverse direction back to the normal position. This movement of the supporting channels together with the columns 20, and bridge heads 21—22 is at the same rate 105 of travel as that of material being operated upon. This forward and return movement is provided for by the following mechanism: 110

On one end of the shaft 31^a, without one of the stringers 30, is fixed a large spur gear 115 116, which meshes with a smaller spur gear 117, secured to a cross shaft 118. This shaft 118, is mounted in bearing blocks 119, which are longitudinally adjustable on the stringers 30 toward and away from the cylinder 120 shaft 31^a. As shown, said blocks are slideable on brackets 120 on said stringers, the adjustment being made by set screws 121 carried by said brackets and engaging the bearing block. Fixed to said shaft 118, near the gear 117, on the opposite side of the stringer 30, is a segmental gear 122, which meshes with a spur gear 123, loosely mounted on a sleeve 124, carried by the shaft 31^a, said gear having a long tooth 125. Rotat- 125 130

able with the gear 124 is a cam 126 upon the periphery of which engages a roller 127, carried on the bottom end of the rod 97 before mentioned, said bottom end of 5 said rod having a sliding bearing in a guide 128 on the top end of the web 129 of the associated bearing block 31^b.

Also fixed to said shaft 128, diametrically opposite the segment and within the plane 10 of the stringers 30, are radial arms 132, which carry inwardly extending pins 133. Said pins in the swing of said arms, engage the ends of associated horizontal arms 134, fixed to a shaft 135 journaled in bearings 15 136 on the stringers 30, to the rear of the shaft 118. Fixed to the extreme ends of the shaft 135 are upright arms 137, arranged in the plane of channels 26. The top ends of said arms are connected by links 20 138 to ears 139 fixed to the bottom of the channels 26. Contractile springs 140 are interposed between the upright arms 137 and upright bars 141 attached to the stringers 30, to return the arms 137 to their normal 25 position, stop lugs 142, on the inner faces of the stringers engaging the arms 134 and limiting the rearward swing of the arms 137.

The material operated on in this instance 30 is the plaster board 35, said board comprising top and bottom coverings of paper 35^a with an intermediate plaster body 35^b adhered thereto. This board is made in a continuous strip and is supported on and is 35 moved by the belts 33-34, through the space between the cutter bars 23-24. To provide a support for the plaster board in the vicinity of the cutter bars, I provide transversely extending rollers 145 which 40 are journaled at their ends in the channels 26-26.

The operation of my improved cutting machine is as follows: The belt 33 carrying the plaster board 35, is driven in any suitable 45 manner and as it passes about the cylinder 31, it rotates the same together with its shaft 31^a. The plaster board passes over the rollers 145 and between the cutter bars and thence onto the belt 34, which delivers 50 the cut pieces or sections to a suitable place of disposal. As the shaft 31^a is thus rotated, the gear 116 thereon will drive the gear 117 and thus rotate the shaft 118. Said gears 116, 117 bear to each other, the same relation 55 that the circumference of the belt cylinder 31 bears to the length of the sections to be cut and therefore by adjusting the shaft 118 towards or away from the shaft 31^a and by substituting thereafter for the 60 gear 117, another gear which meshes with the gear 116, the relation between said gears may be changed at will to either increase or decrease the length of the section to be cut. As the shaft 118 is driven in the direction of the arrows shown in Fig. 10, the ad-

vance end of the segment 122 will engage the finger 125 on the gear 123 to start said gear which will mesh with the gear segment and be driven thereby. Said gear and segment have the same number of teeth so 70 that in every complete rotation of the shaft 118, the gear 123 has been once rotated. The cam 126 will rotate with the gear 123 and its projection will elevate or raise the rod 97.

Said rod will rock the arms 95 and 96 on 75 the strap 94 and swing the outer end of valve arm 86 upwardly against the action of the spring 88. This rocks the valve stem 82 and with it the inlet valve plug 73, when the spaces between the vanes 76 of said plug, 80 will register with the ports 66^a of the valve sleeve 66. Steam under pressure which fills the interior of the valve plug will pass into the piston cylinder 54 and move the piston downwardly, the exhaust valve remaining 85 closed. The downward movement of the piston, through the connecting rod 50 will depress the inner ends of the levers 48, and raise the outer ends thereof about the bearing pins in ears 49, and as the said inner 90 ends engage the top cutter bar 23 through the anti-friction devices 55, and as the outer ends of said levers 48 are connected to the bottom cutter bar 24, said cutter bars will move toward each other on their cutting 95 stroke, compressing the springs 38 between said cutter bars and the abutments 39. As the piston 53 reaches the limit of its power stroke, the rod 100 will through its connection with the levers 48, move the horizontal 100 arm of the bell crank tripping lever 92 downwardly, when the vertical arm thereof will swing away from the short arm 87^a of the lever 87 and thus release the same. The spring 88^a associated with the arm 87 will 105 act through said arm to rock the valve stem connected to the exhaust valve 74, until said arm engages the stop arm 90^a. As the valve 110 plug is thus rotated, the spaces between its vanes will register with ports in the sleeve 67 when the steam will pass through said ports and into the exhaust chamber 64, in the bridge head and then out through the exhaust pipe connected therewith. The pressure on the piston is thus released and the springs 38 will expand to their normal 115 position; moving the cutter bars back into their normal position.

As the cutter bars thus return to the position ready for the next operation, they will 120 through the levers 48 and other connections before described, move the piston 53 upwardly and into its normal position. As the levers thus move, the outer end of the member 110, which is connected to one of said 125 levers 48 by the link 112, will engage the outer end of the arm 87, and move it back into a position where its end 87^a will once more engage beneath and be locked by the shoulder 91 on the bell crank tripping lever. 130

Of course after the roller 127 on the rod 97 leaves the projection on cam 126, the spring 88 will return the arm 86 to its normal position against the stop 90, when the inlet valve 5 will again be closed.

Simultaneously with the swing or rotation of the gear segment 122, the arms 132 on the shafts 118 will also receive their swing or rotation. At a predetermined time in said 10 swing of the arms 132, the pins 133 thereon, will engage the ends of the levers 134 on the shaft 135 and produce a rocking movement thereof. This will swing the upright arms 137 on said shaft against the action of the 15 springs 140. As said arms are connected to the channels 26 by the links 138 and ears 139 as before described, a forward movement is imparted to the channel 26 and the parts mounted thereon, at a speed equal to that of 20 the movement of the plaster board 35 being cut. As soon as the pins 133 pass the arms 134, the springs 140 will tend to move the channel bars back to their normal position, which is reached when the arms 134 engage 25 their associated stop lugs.

The parts are so timed that the cutting mechanism proper on the channels is actuated as the forward movement of the channels begins, the cut having been made before 30 the forward limit of movement of the channels has been reached, the parts of the cutting mechanism proper returning to their normal position as said channels are returning to their normal position. Thus the 35 plaster board is cut while it is moving, so that there is no buckling of the board nor any stoppage of the same. As the knives of the cutting bar have V shaped edges which do not touch each other in the cutting operation, 40 they will cut through the paper coverings and tend to bend the cut edges toward each other as shown in Fig. 19, thus partially binding the cut edge of the board and protecting the plaster body from breakage in 45 the handling to which the sections are naturally subjected.

It is apparent that my improved cutting machine has many advantages:—It cuts the plaster board while it is moving and cuts it 50 from the opposite surfaces thereof, and at the same time produces a cut finished edge wherein parts of the paper coverings are bent towards each other to partly bind the board.

55 The cutter bars having V shaped edges cannot gum up by the adhesion of the plaster material forming the body or core of the board. Furthermore, I am enabled to use a pneumatic fluid as an operating medium and this permits of a quick positive cutting stroke of the cutter bars.

The machine may be quickly changed to cut sections of different length, simply by substituting one gear for another.

65 While in describing my invention, I have

referred to certain detail of mechanical construction and arrangement of parts, I do not wish to be limited thereto except as may be pointed out in the appended claims.

I claim as my invention:

1. In a machine for cutting lengths from a continuously fed strip, a horizontally reciprocable frame, a cutter bar vertically movable in said frame, a member carried by said frame and co-acting with said cutter bar, a fluid actuating member carried by said cutter frame and connected with said cutter bar to move the same towards its co-acting member, means for reciprocating said frame at predetermined intervals, controlling means for said fluid member, and means operable in the forward movement of said frame for actuating said controlling means. 70

2. In a machine for cutting lengths from a continuously fed strip, a horizontally reciprocable frame, a pair of co-acting cutter bars vertically movable in said frame towards and away from each other, a fluid actuating member carried by said cutter frame and operatively connected to said cutter bars, means for reciprocating said frame at predetermined intervals, controlling means for said fluid member, and means operable in the forward movement of said frame for actuating said controlling means. 80

3. In a machine for cutting lengths from a continuously fed strip, a horizontally reciprocable frame, a pair of co-acting cutter bars vertically movable in said frame towards and away from each other, levers operatively connected at their outer ends to said cutter bars, a cylinder and a piston therein carried by said frame, said piston being operatively connected to said levers, 100 means for reciprocating said frame at predetermined intervals, devices providing for adjustment of the length of said intervals, inlet and exhaust valves for said cylinder to and from said cylinder, and means operable in the forward movement of said frame 110 for actuating said valves.

4. In a machine for cutting lengths from a continuously fed strip, a horizontally reciprocable frame, a pair of co-acting cutter bars vertically movable in said frame towards and away from each other, levers operatively connected at their outer ends to said cutter bars, a cylinder and a piston therein carried by said frame, said piston being operatively connected to said levers, 115 means for reciprocating said frame at predetermined intervals, inlet and exhaust valves for said cylinder to and from said cylinder, and means operable in the forward movement of said frame 120 for actuating said valves.

5. In a machine for cutting lengths from a continuously fed strip, a horizontally reciprocable frame, a pair of co-acting cutter 125

- bars vertically movable in said plane towards and away from each other, yielding members interposed between fixed parts of said frame and the ends of said cutter bars, 5
- 5 a cylinder having inlet and exhaust valves and a piston therein carried by said frame, said cylinder being located midway of the ends of said cutter bars, means operatively connecting said piston to said levers, devices actuated in the feeding of said strip for reciprocating said frame at predetermined intervals, and means operable in the forward movement of said frame for actuating said valves. 10
- 15 6. In a machine of the class described, a cutter frame, a pair of co-acting cutter bars vertically movable in said frame towards and away from each other, yielding members interposed between the ends of said 20 cutter bars and fixed parts of said frame, connecting rods at the ends of said cutter bars, said connecting rods being pivotally attached at their lower ends to the ends of the bottom cutter bar, levers movable in 25 the vertical plane of said cutter bars and fulcrumed to the frame above the same, said levers being pivotally attached at their outer ends to the top ends of said connecting rods and having their inner ends pivotally 30 connected to each other, means interposed between said levers and said top cutter bars, whereby the same is depressed with said levers as they operate to lift the lower cutter bar, and means for depressing the inner 35 ends of said levers.
7. In a machine of the class described, a cutter frame, a pair of co-acting cutter bars vertically movable in said frame towards and away from each other, yielding members interposed between the ends of said cutter bars and fixed parts of said frame, connecting rods at the ends of said cutter bars, said connecting rods being pivotally attached at their lower ends to the ends of 40 the bottom cutter bar, levers movable in the vertical plane of said cutter bars and fulcrumed to the frame above the same, said levers being pivotally attached at their outer ends to the top ends of said connecting rods 45 and having their inner ends pivotally connected to each other, antifriction abutments on said top cutting bar engaged by said levers, said abutments being each spaced a distance inward from the fulcrum of its 50 lever equal to the distance said fulcrum is from the pivotal connection of the associated connecting rod, and a fluid controlled piston operatively connected with the inner ends of said levers. 55
- 60 8. In a cutting machine of the kind described, the combination of supporting stringers, a shaft journaled on said stringers, a conveyor belt drum and a gear fixed on said shaft, a frame reciprocably mounted on said stringers, a cutting mechanism carried by said frame, a controlling device for said cutting mechanism, a second shaft mounted on said stringers, a gear on said second shaft, meshing with the gear on said drum shaft, the circumferences of the said gears bearing the same relation to 65
- toward and away from said drum shaft, a gear removably fixed to said second shaft and meshing with the gear on the first shaft, a rock shaft, journaled on said stringers, horizontal and upright arms fixed to said rock shaft, means connecting the upright arms to said frame and radial arms on said second shaft adapted to engage said horizontal arms in the rotation of said second shaft. 70
9. In a machine for cutting lengths from a continuously fed strip, a horizontally reciprocable frame, a cutter bar vertically movable in said frame, a member carried by said frame and coacting with said cutter bar, a motor carried by said frame for actuating said cutter bar to move the same towards its coacting member, means for reciprocating said frame at predetermined intervals, controlling means for said motor, and means operable in the forward movement of said frame for actuating said controlling means. 75
10. In a machine for cutting lengths from a continuously fed strip, a horizontally reciprocable frame, a pair of coacting cutter bars vertically movable in said frame towards and away from each other, a motor carried by said frame for actuating said cutter bars, means for reciprocating said frame at predetermined intervals, controlling means for said motor, and means operable in the forward movement of said frame for actuating said controlling means. 80
11. In a machine of the class described, a cutter frame, top and bottom coacting cutter bars vertically movable in said frame towards and away from each other, levers fulcrumed to the frame above said cutter bars and movable in the vertical plane thereof, rods pivotally attached to the bottom cutter bar and to the outer ends of said levers, means interposed between the inner ends of said levers and the top cutter bar to depress said top cutter bar in one movement of said levers, means for depressing the inner ends of said levers, and expansive devices interposed between the ends of said cutter bars and a fixed part of said frame, which are compressed as said cutter bars 85 move toward each other and which thereafter expand to move said cutter bars away from each other. 90
12. In a cutting machine of the kind described, the combination of supporting stringers, a shaft journaled on said stringers, a conveyor belt drum and a gear fixed on said shaft, a frame reciprocably mounted on said stringers, a cutting mechanism carried by said frame, a controlling device for said cutting mechanism, a second shaft mounted on said stringers, a gear on said second shaft, meshing with the gear on said drum shaft, the circumferences of the said gears bearing the same relation to 95

- each other, as the length of the section to be cut, bears to the circumference of said drum, and means operated in the rotation of said second shaft for actuating said controlling device. 13. In a cutting machine of the kind described, the combination of supporting stringers, a shaft journaled on said stringers, a conveyor belt drum and a gear fixed on 10 said shaft, a frame reciprocably mounted on said stringers, a cutting mechanism carried by said frame, a controlling device for said cutting mechanism, a second shaft mounted on said stringers, a gear on said second 15 shaft, meshing with the gear on said drum shaft, the circumferences of the said gears bearing the same relation to each other as the length of the section to be cut bears to the circumference of said drum, means for 20 adjusting said second mentioned shaft and for changing the gear thereon, to change the relation between the circumferences of said gears, and means operated in the rotation of said second shaft for actuating said 25 controlling means.
14. In a cutting machine of the kind described, the combination of supporting stringers, horizontally spaced drums, mounted on said stringers, conveyor belts for the 30 web to be cut, there being one belt associated with each drum, upright standards carried by said stringers, supporting members reciprocable in said standards, a cutting mechanism mounted on said supporting members between said drums, a controlling mechanism for said cutting mechanism, and means operated in timed relation with one of said 35 drums, for reciprocating said frame and for actuating said controlling mechanism at predetermined intervals. 15. In a cutting machine of the kind described, the combination of supporting stringers, horizontally spaced drums, mounted on said stringers, conveyor belts for the web to be cut, there being one belt associated with each drum, upright standards carried by said stringers, supporting members reciprocable in said standards, a cutting mechanism mounted on said supporting members between said drums, a controlling mechanism for said cutting mechanism, and means operated in timed relation with one of said drums for reciprocating said frame and for actuating said controlling mechanism at predetermined intervals, said last 55 mentioned means being capable of being adjusted to change the periods between said intervals. 16. In a cutting machine, the combination of reciprocable supporting members, upright columns carried by said supporting members, bridge pieces connecting the top and bottom ends of said columns, cutter bars mounted in said columns and vertically movable towards and away from each other, a motor carried by one of said bridge pieces, and means connecting said cutter bars to said motor.

In testimony that I claim the foregoing as my invention, I affix my signature in the presence of two witnesses, this 31 day of October, A. D. 1919.

ALVA W. TYLER.
